UNITED STATES PATENT OFFICE.

FREDERICK O. PEASE, OF CHICAGO, ILLINOIS.

CHIROPODIST'S OR SURGEON'S INSTRUMENT.

1,255,043.

Specification of Letters Patent. Patented Jan. 29, 1918.

Application filed September 24, 1913, Serial No. 791,509. Renewed December 6, 1917. Serial No. 205,894.

To all whom it may concern:

Be it known that I, FREDERICK O. PEASE, a citizen of the United States, residing at Chicago, in the county of Cook and State 5 of Illinois, have invented certain new and useful Improvements in Chiropodists' or Surgeons' Instruments; and I do hereby declare the following to be a full, clear, and exact description of the invention, such as 10 will enable others skilled in the art to which it appertains to make and use the same.

My invention relates to surgical instruments and more particularly to a type of knife or chisel adapted for use by chiropodists. The prime object of my invention 15 is to provide a cutting instrument equipped with a flange adapted simultaneously to guide the instrument to protect the cuticle or tissue adjacent to that which is being cut 20 by the knife edge of the instrument, and to effect a separation of a part of the severed cuticle, nail or tissue from the tissues formerly contiguous thereto. Another object 25 is to equip the blade of a surgical instrument with a guide flange so disposed with reference to the handle of the instrument as to permit the ready and accurate operative manipulation of the said flange by a rotary movement of the handle.

30 The instrument of my invention is particularly adapted for use in operations upon ingrowing toe nails and tissues contiguous thereto, including operations on the periosteum; and is shown in an embodiment particularly adapted to this application in the 35 accompanying drawings, in which:—

Figure 1 is a longitudinal elevation.

Fig. 2 is an enlarged end view of the same.

40 Fig. 3 is an enlarged fragmentary plan view of the same.

Figs. 4 and 5 are enlarged fragmentary elevations of the blade end of the instrument, showing modifications thereof.

45 Figs. 6 and 7 are end views showing a modified form of guide flange and of the handle, respectively.

Fig. 8 is a perspective view showing the instrument as used in operation upon a toe nail.

50 Fig. 9 is a view showing the operation of the guide flange in facilitating the removal of a portion of an ingrown toe nail.

Fig. 10 is a cross section of a modified 55 form of handle.

In the embodiment of Fig. 1, the instrument of my invention consists essentially of a straight sided handle 1 of triangular section having a contracted neck portion 2 connecting the said handle with a blade 3, 60 the said blade being relatively thin and having its face portions disposed approximately in planes passing through one of the longitudinal edges 4 of the triangular handle and at right angles to the blade surface 5 of the 65 handle opposite to the said edge 4. The blade 3 has at one edge a flange 6 extending substantially longitudinally of the handle and projecting laterally of the blade 3 at one or both sides thereof, the said flange 70 also having a toe portion 7 projecting beyond the cutting edge 8 of the blade. The cutting edge 8 is directed toward the adjacent end of the instrument and is preferably disposed at an angle of about seventy 75 degrees with the axis of the handle, so as to form an acute angle with the back or flanged portion of the blade. The edge 9 of the blade opposite to the said back may be dull 80 when this portion is disposed as in Fig. 1 or 80 in Fig. 5; or the portions 8 and 9 may be combined into a single cutting edge of curved outline as in Fig. 4, thereby providing an instrument adapted to effect cutting 85 either by a movement longitudinal with respect to the handle or by a movement of the instrument transverse to the handle in a direction substantially in the plane of one of the faces of the blade.

In using the instrument of my invention 90 for removing the lateral portions of an ingrown toe nail, the handle is grasped as in Fig. 8 with the thumb of the operator resting upon the upper edge 4 of the triangular shank of the instrument and with this shank 95 substantially longitudinal of the nail. The toe portion 7 is then inserted under the nail near one lateral edge thereof and the instrument is pushed forward, thereby severing the portions of the nail disposed at opposite 100 sides of the blade of the instrument. In so doing, the guard or flange 6, the edges of which are preferably rounded, slide upon the tissue underlying the nail and protects the latter from accidental injury by the 105 blade, while the protruding toe portion 7 of the instrument separates the nail from the underlying tissue in advance of the act of cutting the nail. In order to produce a slanting or beveled edge upon the main por- 110

tion of the nail from which the lateral portion is being severed, the instrument may be tilted at an acute angle with the surface of the nail, as in Fig. 9, during the cutting. 5 During the cutting, the lateral portion of the ingrown nail, being relatively narrow, is picked up by the flange 6 and is lifted from the sensitive sulcus in which it is embedded, whereupon a slight pressure of the blade and 10 of the instrument tending to tilt the same in a direction toward the upper edge 9 of the blade will raise the said lateral severed portion 10 of the nail 11 so as to lift the nail portion 10 out of its former embedded position and thereby enable it more readily to 15 be grasped for removal. In any case, it will be obvious that the guard flange 6, because of its thickness, will serve to raise the nail portion from the portion of the toe formerly contacting therewith. The adaptability of the instrument may be increased by 20 providing it with a double-sided flange, as in Fig. 9. Moreover, the same tool can also be used for cutting off the end portion of a 25 nail which is ingrown at its tip by applying the tool transversely to the toe as along the dotted line 12 of Fig. 8.

Where the flange of the instrument of my invention is to be used as a guide or 30 shoulder for effecting the removal of a portion of the matrix or other tissue severed by the cutting edge of the instrument, without requiring a considerable separation of the severed portion from the surfaces formerly contiguous thereto, the flange at the 35 back of the blade may extend only in one direction with respect to the face of the blade, as in Fig. 6 and 7. Moreover, the handle portion or shank of the instrument 40 may be varied in section, as shown by the octagonal section of the instrument of Fig. 7. If the shank is substantially prismatic and triangular in section I preferably dispose the same as in Figs. 2 and 6, as by resting the thumb upon one edge of the triangular shank I am able to rotate the instrument with respect to the axis of the shank with greater delicacy and accuracy than would be possible with a shank having a larger 45 number of sides or having the same other-

wise disposed with respect to the body of the instrument.

While I have shown and described the instrument of my invention as used by chiropodists, I do not wish to be limited to this 55 application of the same, it being evident that embodiments of my invention can be used for a large variety of surgical operations where the flange of my instrument will serve to protect the underlying tissues, or to effect a separation of the severed membranes from the ones beneath the same, or both.

I claim as my invention:

1. An instrument of the kind specified comprising a rod terminating at one end in 65 a cutting blade having convergent side-faces meeting in a cutting edge at one extreme end of the rod, a narrow flange along one edge of the cutting blade and extending beyond the cutting edge of the latter a distance 70 substantially equal to the projection of said flange beyond the side faces of the blade, said flange extending longitudinally relatively to the rod and at a slight incline to the latter, the cutting edge of said blade rising from the upper face of said flange at a 75 slight incline to the plane of the latter.

2. An instrument of the kind specified comprising a rod terminating at one end in a cutting blade having convergent side faces 80 meeting in a cutting edge at one extreme end of the rod, a narrow bevel-edged flange along one edge of the cutting blade and extending beyond the cutting edge of the latter a distance substantially equal to the projection of said flange beyond the side faces 85 of the blade, said flange extending longitudinally relatively to the rod and at a slight incline to the latter, the cutting edge of said blade rising from the upper face of said flange at a 90 slight incline to the plane of the latter.

In testimony whereof I have signed my name in presence of two subscribing witnesses.

FREDERICK O. PEASE.
